EXPANSION JOINT AND METHOD OF
INSTALLING ITGeorge P. Edmonds, Wilmington, Del., assignor to
Bond Manufacturing Corporation, Wilmington,
Del., a corporation of Delaware

Application January 31, 1933, Serial No. 654,524

7 Claims. (Cl. 94—18)

My invention relates to an improved method of constructing sectional paving and like structures and has to do, more particularly, with the formation of a more satisfactory expansion joint 5 for such structures than has been capable of attainment by the methods and means heretofore employed.

In the construction of concrete roads and like structures, it has been the practice to form the 10 structure in spaced sections with a filler strip of a deposit of filler material in the intervening spaces, the filler being capable of yielding under the compressional strain imposed thereon by the expansion of the sections due to increase in temperature. As a rule, such expansion joints have been 15 constructed of plastic, substantially non-compressible filler material, a portion of which, under the strain of section expansion, is unavoidably extruded from the diminished space between the 20 sections. For instance, in constructing concrete roadways, the space between the adjacent sections is usually filled with asphalt or a more or less plastic composition consisting of cellulosic material or other inert filler material and a binder 25 of asphaltum. Such fillers are not materially compressible, but are plastic, with the result that, when expansion forces the end walls of the sections toward each other and the width of the gap or space therebetween is lessened, a portion of the 30 plastic filler is displaced and flows out above the normal road surface, creating an objectionable raised zone or rib at the joint. Frequently, it has been found necessary to go over roads of this 35 character and remove some of the plastic filler which has been forced out at the joint. Subsequently, when contraction of the road sections occurs due to colder weather, the spaces between adjacent sections are widened, the material in the spaces is insufficient to fill the enlarged gaps, and 40 the material previously extruded from the spaces during warmer weather, even though allowed to remain on the road surface, does not return to the spaces, with the result that unfilled gaps are created between the sections. These gaps not 45 only render the road surface rough, but particles of incompressible material gain entry into the gaps in lieu of the original filler and, thereby, practically eliminate the expansion joints. Furthermore, some commonly employed fillers, such 50 as asphalt-impregnated roofing paper and the like, while theoretically capable of being compressed, in practice, because of intermixture with dirt and like non-plastic and non-resilient material, do so only under extreme pressures, with 55 the result that expansion of the sections is often

accommodated by the heaving thereof from the road bed and the formation of cracks therein.

Theoretically, in order to provide a satisfactory cork composition joint, it should be necessary merely to make a cork strip having a thickness 60 equal to the maximum width of the space between sections, and slip it in place. From the standpoint of actual practice, however, such a method is extremely difficult if not impossible of execution. In the first place, concrete paving is usually laid in comparatively warm weather, and the sections thereof are not contracted. Moreover, such paving is subject to linear variation in accordance with its moisture content. It is self-evident then, that a cork strip, installed as the 65 gap filling element, even though initially snugly fitted and cemented in place will, after the advent of colder and drier weather, no longer snugly fill the gap. A conventional cork composition filler strip will not fill an expansion gap which 70 has widened since the time the strip was placed. As a result, such a strip becomes loose in the widened gap.

It is, accordingly, a primary object of my invention to provide a method of constructing expansion joints employing a cork or cork composition 75 filler strip, which joint will be fully compensating—that is, will permit the sections to freely and easily expand to their full extent in accordance with rising temperature, yet which will itself automatically and adequately expand to completely fill the widening gap between sections when they are contracting in accordance with declining temperature.

It is an object of my invention to provide a 80 simple, easy and inexpensive method of making permanent cork-strip expansion joints in sectional paving and like structures, which joints, once installed, require no caulking or further special attention.

It is an object of my invention to provide a 85 cork expansion joint strip for sectional paving and like structures, which strip is inherently self-anchoring.

A further object of my invention is to provide a 90 cork-strip expansion joint for sectional pavements and like structures which is inherently water-tight and which will, to a satisfactory extent, prevent the entry of water into the space between pavement sections and preclude the 95 weathering action thereof, and possible formation of ice therein.

Further objects, and objects relating to details 100 and economies of construction and use, will definitely appear from the detailed description to 110

follow. In one instance, I accomplish the objects of my invention by the devices and means set forth in the following specification. My invention is clearly defined and pointed out in the appended claims.

A structure constituting a preferred embodiment of my invention is illustrated in the accompanying drawing forming a part of this specification, in which:

10 Figure 1 is an end view of the highly resilient cork composition filler strip employed in carrying out of my method, said strip being shown in its normal, uncompressed state;

15 Fig. 2 is a diagrammatic view of the same filler strip disposed in the press, prior to subjecting it to lateral compression;

20 Fig. 3 is a diagrammatic view of the same filler strip and press, said strip being subjected to a compression stress effecting its reduction to 50% its original thickness;

25 Fig. 4 is an end view of the same strip immediately after its removal from the press where it has been subjected to a constant 50% reduction in thickness for a period of approximately twelve hours;

30 Fig. 5 is a cross-sectional view of the strip shown in Fig. 5 a few minutes after its removal from the press and disposed in the gap between a pair of concrete sidewalk sections; and

35 Fig. 6 is a similar cross-sectional view of the same sidewalk sections and filler strip a few hours later, showing the strip expanded into complete filling and self-anchoring relation with the sections.

40 The same reference numerals refer to the same parts throughout the several views.

45 In its broader aspect my invention relates to the formation of expansion joints in sectional paving and like construction, such as floors, sidewalks, and highways, and consists first in spacedly laying sections of such size and form that, within the extremes of temperature to which the structure will be subject, expansion and contraction may take place without heaving or cracking of the sections, and second, in preforming, of cork or equivalent highly resilient material, a filler strip for each expansion gap between adjacent sections, which strip has the characteristic of being temporarily of less thickness than the instant or normal gap between the adjacent sections and of expanding after insertion in the gap, thereby automatically filling the gap, and anchoring itself therein.

50 More specifically, and as applied to sectional concrete paving construction, my invention consists first in laying concrete sections 10, 11 of the usual form and size, and spacing the sections from each other so that gaps 12 are provided therebetween which will accommodate thermal expansion of the sections under the temperature changes to which the paving will be subject. In casting the sections in situ upon the pavement bed 13, the usual care must be taken to prevent the formation of a web or bridge 55 across the gap which would interfere with free expansion of the sections. The width of the gaps will depend, among other factors, upon the character of the material of which the sections are formed, the coefficient of linear expansion thereof, the expected maximum variation in temperature, and the spacing between the joints. I have found that, for general purposes and general conditions, a filler strip 14 of highly resilient cork composition having a thickness of three-fourths of an inch is very satisfactory. Such a

strip, of the composition hereafter to be specified, is capable of compensating for variations in gap width of substantially one-half of an inch without permanent impairment of the resiliency of the strip and without setting up compressive stresses in the sections which would cause the heaving thereof from the bed. In using a filler strip of such composition and dimension, it is necessary merely to provide expansion gaps at such intervals and of such width that, under maximum section contraction, each gap will be slightly less than three-fourths of an inch and under maximum section expansion each gap will be not less than one-fourth of an inch. General experience with the expected temperature variation and the material of which the sections are made will enable the builder to allow for thermal contraction subsequent to construction. Thus, the proper thickness of the gap form to be used, when casting sectional concrete paving, may be readily computed for any given thickness of filler strip.

55 Although theoretically the strip 14 may be formed of virgin cork, such cork cannot readily be obtained in the desired size and length, and for reasons of economy and serviceability, I prefer to make the strip of cork composition consisting of comminuted or granulated cork agglomerated with a thermo-setting binder and formed by moulding in an extrusion machine. A suitable composition which I have found satisfactory for the manufacture of filler strips adapted for use in accordance with my invention consists of 300 pounds of comminuted cork agglomerated with a thermo-setting binder consisting of 100 a phenolic condensation product formed by the reaction of phenol and formaldehyde. This binder sets when heat is applied, for instance, in the extrusion machine, and the resulting composition is compressible but not plastic or displaceable under pressure. As an enduring plasticizing agent, I use, in this mixture, some 60 pounds of diethylene glycol, which also serves as a softening agent for the cork particles and renders them more flexible, with the result that the composition is more easily compressible than pure, untreated virgin cork. To this mixture there is added any one of the numerous lubricants used in the cork composition art. The procedure employed in the manufacture of the composition from the above ingredients is preferably as follows: The phenol, formaldehyde and diethylene glycol are mixed and heated in a copper-jacketed kettle. When the mixture has reached the required temperature, sodium hydroxide is added as a catalyst. The temperature is maintained and heating continued until a sample of the liquid will set, in boiling water, in ten minutes. The reaction is then interrupted, and the intermediate product, which is a heavy liquid, is immediately mixed with the cold ground cork in the proportion of about 160 pounds of the liquid to 300 pounds of the cork. These proportions may be varied, however. The mixture thus provided is then taken to the extrusion machine, for instance, such as shown in United States Letters Patent No. 1,453,617, issued May 1, 1923. In such a machine the mixture is confined in a mold at a temperature of about 300° F., which completes the reaction and causes the comminuted cork to be agglomerated by the binder, providing a cohesive mass of the shape desired.

60 Instead of the binder mentioned in the above formula, any one of a number of other thermo-

setting binding agents may be used for agglomerating the cork particles. As an enduring plasticizing and cork-softening agent, other materials may be employed, among which are glycerine and ethylene glycol.

As has been heretofore stated, a suitable strip thickness for general application is three-fourths of an inch. The strip should preferably be as deep as the thickness of the paving section and should extend the full length of the expansion gap, the upper surface of the strip being flush with the adjacent sections, and providing therewith, a substantially uninterrupted paving surface. It is obvious, of course, that the gap might, if desired, be filled with two or more strips, superposed, end on end, or side by side, one or all of which may be precompressed. While the strip may have any desired cross-sectional form, for ease of application as well as simplicity of manufacture, I have found the disclosed rectangular form to be entirely satisfactory.

In accordance with my invention, the cork composition strip 14 having a normal thickness of three-fourths of an inch is placed in a press illustrated diagrammatically in Figs. 2 and 3 and comprising parallel stationary top and bottom walls 15 and 16 and parallel side walls 17 and 18 movable toward each other by any suitable means of applying pressure (not shown). After placing the strip 14 in the press, it is reduced to a thickness of approximately 50% its normal thickness by subjecting it to a lateral pressure of approximately 170 pounds per square inch. This pressure and reduction in thickness is maintained for a period of approximately twelve hours, whereupon the strip is removed. By means of the prolonged compression of the strip to but 50% its normal volume, upon release the strip will not immediately expand to its original normal thickness but will, for some minutes thereafter, recover only some 45% of its enforced reduction in thickness, as shown in Fig. 4. Thus, the strip will have, for a short period after its removal from the press, a thickness of not materially more than one-half of an inch, and if a gap of some three-fifths of an inch has been provided between the sections, the facile insertion of the strip in the gap, as illustrated in Fig. 5, is assured. The partial paralysis of resiliency, or self-maintained deformation of the strip is, however, not permanent and usually in the course of less than one hour after its release from the press it will have expanded or recovered sufficient of its original normal thickness to fill the gap and anchor itself therein by frictional contact with the gap-defining end walls of the sections. Such a strip, left to expand without restriction, will ultimately recover 95% or more of its original thickness. It is important, therefore, only to be certain that the original thickness of the strip is some 5% greater than the maximum width to which the gap between the sections will expand under lowest temperatures. Although a filler strip of the composition set forth may not immediately recover its original thickness after having been subjected to compression to 50% of its original thickness for protracted periods, the resiliency of the strip, within the limits to which it will expand and can be compressed by moderate pressures, is substantially the same as that of the strip prior to its processing in accordance with the present invention. Tests have been conducted to determine the effect of lessening and increasing the period of compression to 50% nor-

mal or original strip thickness. Generally speaking, the rate of recovery, both initial and ultimate is inversely proportional to the length of time compression is maintained. A strip held under compression for two months initially recovered, upon release, but 58% its original thickness. In less than one hour after release, it had recovered more than 60% its original thickness. Some fifteen hours elapsed before it had recovered 65% of its original thickness. In four days it had recovered some 80% of its original thickness, and after one month it had expanded to approximately 90% its original thickness. The period of compression to 50% original thickness, is therefore, not critical and may be varied in accordance with requirements. Likewise, a cork strip of the specified composition may be subjected to pressures either less or more than 170 pounds per square inch, though not over a broad range comparable to that relating to the time factor. Cork strips of the composition specified have been subjected to pressures amounting to thousands of pounds per square inch. There are limits, however, beyond which serious and more or less permanent impairment of resiliency results. Suffice it to state that pressures of from 1 to 150 pounds per square inch effect a substantially uniform progressive reduction in strip thickness; 150 pounds pressure per square inch effecting a reduction in strip thickness to approximately 52% of normal. From 150 to 600 pounds pressure there is effected a material though increasingly less marked reduction from 50% to 33%. The pressure required to effect greater reduction in thickness than 50%, as well as the permanent impairment of resiliency resulting from greater compression, render more or less undesirable the practice of my method by thickness reductions materially greater than 50%.

I am aware that my method may be varied considerably without departing from the scope of my invention. It may be employed in replacing or renewing expansion joints in old structures as well as in the construction of new structures. Other materials such as virgin cork may be used in the fabrication of the filler strip. Moreover, because of irregularity of expansion gap width or unusual seasonal variations in temperature, a strip of greater thickness than three-fourths of an inch may be desirable or necessary. I, therefore, claim my invention broadly as indicated by the appended claims.

What I claim is:

1. The method of constructing sectional paving and like structures comprising: laying sections of such size and form as can, within the extremes of temperature to which the structure will be subject, freely expand and contract without the development of destructive internal stresses, spacing said sections so that a substantial gap is defined therebetween even when the sections are under maximum expansion, forming, of cork or equivalent highly resilient material, a filler strip having a normal thickness greater than the width of the gap defined by the sections under maximum contraction, compressing said strip to such an extent and maintaining said compression for such a period as to effect temporary, self-maintained deformation therein characterized by a reduction in the thickness thereof to less than the normal width of the gap defined by said sections, placing said strip in said gap while still in its temporary, 150

self-maintained, deformed state, and allowing said strip to expand and fill said gap.

2. The method of constructing sectional paving and like structures comprising: laying sections of such size and form as can, within the extremes of temperature to which the structure will be subject, freely expand and contract without the development of destructive internal stresses, spacing said sections so that the width 10 of the gap between the sections under maximum expansion will not be materially less than one-third the width of the gap defined by the sections under maximum contraction, forming, of cork or equivalent highly resilient material, a filler strip 15 having a normal thickness greater than the width of the gap defined by the sections under maximum contraction, compressing said strip to such an extent and maintaining said compression for such a period as to effect temporary, self-maintained deformation therein characterized by a 20 reduction in the thickness thereof to less than the normal width of the gap defined by said sections, placing said strip in said gap while still in its temporary, self-maintained, deformed state, and allowing said strip to expand and fill 25 said gap.

3. The method of constructing sectional paving and like structures comprising: laying sections of such size and form as can, within the 30 extremes of temperature to which the structure will be subject, freely expand and contract without the development of destructive internal stresses, spacing said sections so that the width of the gap between the sections under maximum expansion will not be materially less than one-third the width of the gap defined by the sections under maximum contraction, forming, of 35 highly resilient cork composition, a filler strip having a normal thickness greater than the width of the gap defined by the sections under maximum contraction, compressing said cork strip to such an extent and maintaining said compression for such a period as to temporarily 40 paralyze its power of rapid recovery and effect a material though temporary self-maintained 45 reduction in thickness to less than the normal width of the gap defined by the sections, placing said cork strip in said gap while still in its reduced state, and allowing said strip to expand and fill said gap.

4. The method of constructing sectional paving and like structures comprising: laying sections of such size and form as can, within the extremes of temperature to which the structure 55 will be subject, freely expand and contract without the development of destructive internal stresses, spacing said sections so that the width of the gap between the sections under maximum expansion will not be materially less than one-third the width of the gap defined by the sections under maximum contraction, forming, of 60 highly resilient cork composition, a filler strip having a normal thickness greater than the width of the gap defined by the sections under maximum contraction, compressing said cork strip to substantially one-half its normal thickness, maintaining said strip thus compressed 65 for a period sufficient to temporarily paralyze its resiliency so that, upon release from compression and for a considerable time thereafter, it will have a thickness materially less than 70 the gap between said sections under maximum contraction, inserting said strip, thus temporarily reduced in thickness, at a time when said

gap is greater in width than the reduced thickness of said strip, and allowing said strip to expand, fill said gap, and anchor itself in place therein.

5. The method of constructing concrete highways comprising: laying monolithic slab sections having a length such that, within the extremes of temperature to which the highway will be subject, the maximum seasonal variation in length due to thermal expansion and contraction will be not materially greater than one-half of an inch for each section, spacing said sections so that a gap of at least one-fourth of an inch will be defined between adjacent sections when under maximum expansion, forming, of cork composition compressible to substantially one-third its normal volume without permanent destruction of its resiliency, a filler strip having a normal width of approximately three-quarters of an inch, compressing said strip to a width of approximately three-eighths of an inch, maintaining said compression for such a period that the resiliency of said strip is temporarily paralyzed and when released and for a short period thereafter, said strip will expand to approximately but three-fourths its original normal thickness, releasing said strip from compression at a time when its thickness upon release would be less than the instant width of said gap, and immediately placing said strip in said gap and allowing it to expand 100 and anchor itself therein.

6. The method of forming resilient expansion joints in sectional paving and like structures comprising: preforming, of highly resilient cork composition, a filler strip having a thickness approximately five per cent greater than the width of the gap defined by the paving sections under maximum contraction, compressing said strip so as to reduce its thickness to substantially fifty per cent its original thickness, maintaining said compression for a sufficient period of time to temporarily paralyze the resiliency of the strip and cause it to initially recover, when released, approximately but fifty per cent of its reduction in thickness, placing said strip in the gap between 110 said sections shortly after it has been released and while its thickness is less than the width of said gap, and allowing said strip to recover as much of its original thickness as is permitted by said sections, thereby filling said gap and anchoring itself therein.

7. A self-anchoring filler element for installation in the expansion gap between adjacent sections of a sectional pavement or similar structure to provide, with said sections, a smooth uninterrupted surface under all actual conditions of section expansion and contraction comprising: a strip of cork composition consisting of highly resilient comminuted cork particles agglomerated with a binder, the cork particles of which have 130 been highly compressed in one direction and thereby strained to such an extent as to have temporarily lost their characteristic property of rapid recovery to original size when released, said strip being of slightly less thickness than the width of 140 the expansion gap for which it is adapted, and having the characteristic, if externally unrestricted, of gradually expanding to a thickness of approximately 130 per cent of its initial thickness whereby wedging or anchorage between the 145 paving sections defining the gap may be automatically effected by simply laying the strip therein before said expansion has taken place.

GEORGE P. EDMONDS.
